CLAIM

The ornamental design for a pet hair remover, as shown and described.

DESCRIPTION

FIG. 1 is a perspective view of a pet hair remover showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the pet hair remover that form no part of the design claim but are included for illustrative purposes.

1 Claim, 8 Drawing Sheets
